UNITED STATES PATENT OFFICE

92,326

DESIGN FOR A FACE PLATE FOR ELECTRICAL DEVICES

Harry V. Steele, Auburn, and Victor R. Despard,
Syracuse, N. Y., assignors to Pass & Seymour,
Inc., Syracuse, N. Y., a corporation of New York

Application August 8, 1932, Serial No. 44,556

Term of patent 14 years

To all whom it may concern:

Be it known that we, HARRY V. STEELE and VICTOR R. DESPARD, citizens of the United States and residents of Auburn, county of Cayuga, State of New York, and Syracuse, county of Onondaga, State of New York, respectively, have invented a new, original, and ornamental Design for Face Plates for Electrical Devices, of which the following is a specification, reference being had to the accompanying drawing, forming a part thereof, and in which

Figure 1 is a face view of a face plate for electrical devices having the ornamental design of the present invention applied thereto;

Figure 2 is an edge elevation thereof; and Figure 3 is a fragmentary sectional view on line 3-3 of Figure 1, shown on a somewhat enlarged scale.

The dominant feature of the face plate design resides in the combination of the border and the ornamentation of the surface contained within it as applied to conventional forms of face plates.

We claim as our invention:

The ornamental design for a face plate for electrical devices substantially as shown and described.

VICTOR R. DESPARD.
HARRY V. STEELE.
